UNITED STATES PATENT OFFICE.

LEVI M. FOX, OF ALBION, IOWA.

CAR-COUPING.

SPECIFICATION forming part of Letters Patent No. 394,165, dated December 11, 1888.

Application filed December 31, 1887. Serial No. 259,511. (No model.)

To all whom it may concern:

Be it known that I, LEVI M. FOX, a citizen of the United States of America, and a resident of Albion, in the county of Marshall and 5 State of Iowa, have invented an Automatic Car-Coupling, of which the following is a specification.

My object is to avoid the dangers and accidents incident to persons going between 10 cars to couple and uncouple; and my invention consists in the construction and combination of a link-governing device, a pin-governing device, and a self-adjusting pin-support, with a draw-head and car, as hereinabove set forth, pointed out in my claim, and 15 illustrated in the accompanying drawings, in which—

Figure 1 is a sectional view showing the 20 link-governing mechanism in its normal position, the pin-support pressed back by the link, and the pin dropped through the link, as required, to secure a link of common form by means of a common coupling-pin. Fig. 2 is a perspective view of the link-governing 25 device. Fig. 3 is a sectional view showing the pin-support in position, as required, to retain the coupling-pin elevated in such a manner that when a coupling-link carried by a draw-head on another car enters the mouth 30 of the draw-head it will press the link-support backward, so the pin can drop through the link. Fig. 4 is a view of the end of a car, showing my complete invention applied, as required, for practical use. Fig. 5 shows 35 the pin-governing device applied and the pin suspended in an inoperative position.

A represents a draw-bar, adapted to be fixed to a car in a common way.

B is a vertical extension at the front and 40 top of the bar, through which a bore is made to intersect the link-cavity.

C is a false floor and link-governing device that consists of two parallel curved bars, d, that are connected by a cross-bar, d', as 45 clearly shown in Fig. 2. The device is preferably cast complete in one piece of malleable iron or steel, but can be forged from wrought-iron. Perforations in the floor of the link-cavity allow the free ends of the 50 bars d to pass through downward, as clearly shown in Figs. 1 and 3, and in such a manner that it can be readily operated, as required, to manipulate and direct a link into the head of a mating draw-bar.

f is a rock-shaft that has a bend, f', at its 55 center and handles at its ends, and is attached to a car in such a manner that the bent center will swing forward to engage the ends of the link-governing device, as indicated by dotted lines in Fig. 1, to press the 60 said ends forward and thereby elevate the front end of the link to direct it into a mating draw-head.

g is a sliding pin-support fitted in a corresponding slot in the draw-bar that intersects 65 the link-cavity.

g' is a spring placed in the rear of the pin-support in such a manner that it will, in its normal condition, hold the pin-support under the pin, as shown in Fig. 3. A slot, h, in the 70 pin-support g, and a pin, i, extending through the slot and fixed to the draw-bar, restricts the backward and forward motions of the pin-support.

J J are levers pivoted to the front of the 75 car and connected with the coupling-pin k by means of a chain in such a manner that a person at either side of the car can operate the levers to lift the pin, as required, to uncouple. A rod or bar, m, connected with one 80 of the levers J and extended upward, allows a person on top of a car to operate the levers and lift the pin, and a joint at the top end of the rod allows the top portion, n, to fall on the 85 roof of the car whenever the pin-rod is lifted in such a manner that it will retain the pin elevated and inoperative, as required, to prevent coupling.

r is a sleeve fixed to the top of the car, as shown in Fig. 5, through which the rod m is 90 operated. A slot in the top of this bearing and sleeve allows the hinged top n of the rod m to fall over upon the car, and the complete sleeve covers and protects the joint in the rod.

I claim as my invention—

The automatic car-coupling comprising a draw-bar having a sliding pin-support, g, a link-governing device, C, resting upon the floor of the link-cavity with its ends extending down through openings in said floor, a 100 rock-shaft having a bend, f', levers J J, and the jointed rod m n, constructed and combined with a car to operate in the manner set forth.

LEVI M. FOX.
